UNITED STATES PATENT OFFICE.

PAUL C. GRAHAM, OF LONG BEACH, CALIFORNIA, ASSIGNOR OF ONE-HALF TO JAMES ALVA BUTLER, OF LONG BEACH, CALIFORNIA.

MATERIAL BATCHER.

Application filed November 23, 1926. Serial No. 150,272.

My invention relates to a device in which a definite amount of material may be measured, and my invention is particularly applicable to the measuring of various grades 5 of crushed rock or the like. It is well known that the proper forming of concrete is largely dependent upon the proper mixing of the dry aggregate of which the rock is a large portion. In order that the concrete 10 may be uniform throughout the entire structure each batcher which is made must be identical with the preceding one. In my batcher it is possible to accurately measure the various amounts of different sized rock 15 which goes into the making of the concrete.

An object of my invention is to provide a material batcher which will properly proportion and measure these materials.

Another object is to provide a diaphragm 20 in the batcher by means of which the proportions of the different materials may be varied; but said diaphragm does not vary the total volume of the batcher.

A further object is to provide a batcher 25 having a diaphragm or diaphragms therein so that a plurality of materials may be proportioned and measured, and if only one material is used then the diaphragm may be employed to measure the contents.

A still further object is to provide a rapid 30 and effective means of varying the capacity of the batcher.

Still another object is to provide a batcher 35 the gates of which are easily and quickly controlled.

A still further object is to provide a batcher which is simple in construction and effective in operation.

Other objects, advantages and features of 40 invention may appear in the accompanying drawings, the subjoined detailed descriptions, and the appended claims.

In the drawing—

Fig. 1 is a side elevation of my batcher.

Fig. 2 is a transverse sectional view of the same.

Fig. 3 is a fragmentary side elevation of the adjusting means.

Fig. 4 is a plan view of my batcher with 50 one of the gates removed.

Fig. 5 is a side elevation of the adjustable diaphragm.

Referring more particularly to the drawings:

My batcher 1 comprises an upper section 2

preferably rectangular in form. This section is rigidly secured to the bottom of the bunkers 3. A lower section 4 telescopes over the upper section 2 and is adapted to be raised and lowered to vary the capacity 60 of the batcher as will be further described. A pair of gates 5, 6 are hinged at 7 and 8 respectively, to the lower edge of the bottom section 4 and are adapted to swing downwardly when dumping and to swing in to a 65 closed position when the batcher is being filled. These gates are controlled by suitable means such as the sling 9 which is operated from a suitable lever or the like located close to the ground. 70

The lower section 4 is supported by four chains 10, said chains being secured in their lower ends to an eye bolt 11, said bolt extending through an angle iron 12 or the like secured to the lower section, and a nut 13 75 screws on to the bolt and bears against the angle iron, thereby securing the lower end of the chain 10 in position. It will be evident that fine adjustment of the lower section 4 relative to the upper section 2 may be 80 obtained by screwing the nut 13 up or down on the eye bolt 11, thereby raising or lowering the section 4.

For rapid adjustment, plates 14 are provided on the upper section 2 which plates are provided with a slot 15 therein, through which the chain 10 passes and which is caught in the lower restricted portion of the slot; thus by raising or lowering the chains 10 an adjustment of the section 4 is accomplished. 90 The chains 10 being all of identical construction, each link will be the same in length and therefore an accurate calibration may be made by stating the number of links to be raised or lowered to give the required capacity of the batcher. 95

To charge the batcher I provide one or more sliding gates 16, which gates are positioned on the top of the upper section 2 and immediately under the bunkers 3. The 100 bunker is provided with outlet openings 17 and the gates 16 are provided with ports 18 which are adapted to register with said openings, thereby permitting the batcher to be filled. In order that the gates 16 may be 105 easily moved, I provide a line of rollers 19, 19 on either side of the gates. These rollers rest on angles 20 extending the length of the section 2 and which are secured thereto. Angles 21 are provided on the bottom of the 110

gates 16 to hold the rollers in position. These lines of rollers are somewhat shorter than the length of the batcher since as the gates 16 are moved outwardly the rollers will 5 also travel forwardly but the rollers will only travel one-half the distance that the gates do; thus enabling me to use rollers requiring very little, if any, lubrication, and materially increasing the useful life thereof. 10 It will be seen that as the gates 16 are moved outwardly the ports 18 will be brought into registry with the outlets 17, thereby permitting the material from the bunkers to flow into the batcher and fill the same. 15 It is obvious that I may employ one or more to control the material flow into the batcher, and that the batcher may be of such size as is desired for the particular material handled. I have here shown a batcher adapted to handle only two definite kinds or sizes of material.

As here shown I provide a single-adjustable diaphragm 22 extending across my batcher, the object of which is to vary the proportions of the two materials in the batcher. When materials are fed into a batcher by gravity the upper portion thereof will be frusto-conical in shape. Therefore, it is essential when varying the proportions of the two chambers within the batcher that the separating wall shall not vary relative to this conical section. Otherwise, the total capacity of the batcher would be varied. In my batcher the diaphragm 22 is hinged 25 at 23 in the center and the upper section of said diaphragm remains substantially vertical at all times; while the lower section is swung to either side to get the required proportions of the various materials. 30

40 The upper part of the diaphragm 22 comprises a pair of plates 24, 25 which are adjustable relative to each other, said adjustment being provided for by a plurality of aligned holes 26 in the two plates, and the two plates are held together by bolts extending through said holes. The lower part of the diaphragm comprises a pair of plates 27, 28 which are also adjustable relative to each other by means of holes 29 in the same manner as previously described. 45

50 A plurality of holes 30 are provided adjacent the lower edge of the section 4 and a rod passes between opposite of said holes, and through the bottom loops 31' of the diaphragm, thus holding said diaphragm in any given position. It will be seen that the diaphragm may be moved to either side of a central vertical line through the batcher by merely extending or shortening the plates 55 as desired; thus giving the required proportions of the two or more materials in the batcher. The upper end of the diaphragm 22 is secured adjacent the top of the section 2 and at the center thereof by means of a rod 60

65 31 or the like.

It is evident from the foregoing description that I may construct a batcher into which three, four or more different materials may be entered, and by means of adjustable diaphragms the various materials may be proportioned as desired. While I have shown and described a batcher having two compartments, I do not wish to limit myself to this exact construction as I may employ more or less than two. And it is to be understood that I may vary the construction within the scope of the appended claims. 75

Having described my invention, I claim:

1. A batcher comprising a pair of telescoping sections, means to adjust said sections 80 relative to each other, intake means for said batcher, outlet means for said batcher, means to vary the proportions of materials in said batcher, said last named means comprising a diaphragm in said batcher, and means to 85 variably position said diaphragm in the batcher.

2. A batcher comprising an upper stationary section, a lower section telescoping over said upper section, means to adjust said lower section relative to the upper section, a diaphragm in said batcher, means to selectively secure said diaphragm in various positions in the batcher, gates on the top of said batcher, and gates on the bottom of 95 said batcher.

3. A batcher comprising an upper section, a lower section telescoping over the upper section, means to adjust the lower section relative to the upper section, inlet means at 100 the top of the batcher, outlet gates at the bottom of the batcher dividing said batcher into compartments, a diaphragm in the batcher, said diaphragm comprising a plurality of plates, means to adjust said plates 105 relative to each other, a hinge at the center of said diaphragm, and means to adjustably secure the lower end of said diaphragm in the batcher, whereby the size of the compartments in the batcher are varied. 110

4. A batcher comprising an upper section, a lower section telescoping over the upper section, means to adjust the lower section relative to the upper section, inlet means at the top of the batcher, said inlet means comprising gates each having an inlet port therein, and a line of rollers mounted in said batcher upon which the gates rest, said line of rollers being of lesser length than the length of the batcher, outlet gates at the bottom of the batcher, a diaphragm in the batcher dividing said batcher into compartments, said diaphragm comprising a plurality of plates, means to adjust said plates relative to each other, a hinge at the center 120 of said diaphragm, and means to adjustably secure the lower end of said diaphragm in the batcher, whereby the size of the compartments in the batcher are varied. 125

5. A batcher comprising an upper section, 130

a lower telescoping section, intake means at the top of the batcher, gates on the bottom of the batcher, chains secured to said bottom section, plates secured to the upper section having notches formed therein into which notches the links of the chain are adapted to rest thereby securing the lower section in position, eye bolts secured to the bottom of said chains, said bolts being threaded through the lower section whereby fine adjustment of the batcher may be made,

a diaphragm in said batcher comprising a plurality of plates, said diaphragm dividing the batcher into compartments, means adjustably securing adjacent plates together, and means adjustably securing the lower end of the diaphragm to the batcher, whereby the size of the compartments in the batcher are varied. 15

In testimony whereof I affix my signature.

PAUL C. GRAHAM.
